UNITED STATES PATENT OFFICE.

LYMAN DERBY, OF NEW YORK, N. Y.

IMPROVEMENT IN BANK-LOCKS.

Specification forming part of Letters Patent No. 21,947, dated November 2, 1858.

To all whom it may concern:

Be it known that I, LYMAN DERBY, of the city, county, and State of New York, have invented certain Improvements in Locking or Bolting the Doors of Banks, Bank-Safes, or other places, by means of an automatic machine arranged on the inside of the safe; and I do hereby declare the following to be a full description of the same.

The nature of my invention consists in securing to the inside of the door a bar or series of bars or cross-bars so arranged as to revolve on one common center, which is fastened in the door in such a way as to permit a handle or knob being attached to it on the outside of the door to latch the bars when the door is closed; also, the mode of constructing and operating a spring-latching lever by means of a simple clock-movement, so that however ponderous the locking-bars may be the power of an ordinary clock-movement will be sufficient for the purposes required, and as each of the parts—to wit, the locking-bars, pendulous latching-lever, and clock-movement—are detached and operate independent of each other, except in the operation of unlatching the locking-bars, it can be seen at once that the greatest amount of security is attained by the least possible amount of mechanism and power.

But to describe my invention more particularly I will refer to the accompanying drawings, forming a part of this specification, the same letters of reference, wherever they occur, referring to like parts.

Figure 1 is an interior view of a safe, looking in from the back of it, and exhibiting the cross-bars, latching-levers, and automaton. Fig. 2 is a front elevation of the safe, exhibiting the handle secured in the axis of the cross-bars on the interior of the door of the safe for latching them. Fig. 3 is a transverse cut-section of the safe, through the line *xx*, Fig. 1.

Letters A are representations of the walls of an ordinary iron safe, and B the door thereof. To the inside of the door is secured a cross-bar, C, on an axis, D. This axis is arranged eccentric to the true center of the cross. The object of this is to cause the bars, immediately on being released from the latching-lever, to withdraw from the recesses in the

sides of the safe, in consequence of the preponderance of weight in the back end of the cross-bars. It will be obvious that this same effect can be produced by weighting the back end of the bars should the axes be in their true center.

Attached to the axis on the outside of the door of the safe is a handle, E. The object of this handle is to latch the bars when the door is closed, the ends of which are held in brackets F F, secured on the inner surface of the door, so as not only to prevent the bars rotating too far, but at the same time to support and strengthen them. It is not absolutely necessary that this handle should be centered in the cross-bars for the purpose of latching them, or that the axis of the cross-bars should extend entirely through the door, as there are many very obvious ways of latching the bars; but I do not think a more simple mode can be suggested in view of the design of having the bars to drop of their own gravity when unlatched.

Letter G is a pendulous spring-latch lever, secured to the inside of the safe by a center pin, H. This center pin is arranged so as to be on a line or nearly so with the end of the cross-bar. The object of this is to have the latch *g²* as near as possible on a line with the center pin, that any power applied to lift the cross-bars to open the door will have to be exerted upon the pin before it could be opened, while at the same time a small spring, I, may be applied to hold the latch *g²* in whatever position the safe may be in upon the end of the bar, to keep it locked till the detaching-pin J in the dial-plate K, comes round and raises the long arm of the latching-lever G, to let the bars drop from the recesses in the sides of the safe.

Letter L represents the frame of an ordinary clock-movement, which is exhibited as secured in the chamber of the safe.

In practically building safes for the application of my method of locking them, recesses will be formed in the sides of the safe in such a way as to be out of the way entirely, and the clock-movements will be concealed within them.

As any ordinary clock-movement not using a pendulum can be used for unlocking the

door of the safe at stated times, I do not deem it material to describe the clock-movements, otherwise than to specify it under the general name of a clock-movement, and therefore claim the use of any such application of the same for the purposes set forth.

Having now described my invention, I will proceed to set forth what I claim and desire to secure by Letters Patent of the United States.

1. The use of the bars or cross-bars secured on an axis eccentric to its true center for the purpose of obtaining gravity to unlatch them, in combination with the inside of the door of a safe or other place, substantially as hereinbefore set forth.

2. The use of a pendulous latch-lever secured to the inside of a safe, in combination with the bars or cross-bars operating, as hereinbefore set forth, on the inside of the door of a safe, and for the purposes described.

3. The use of the application of a clock-work movement, in combination with an inverted V-shaped pendulous latch-lever and bars or cross-bars on the inside of the door of a safe, for the purposes hereinbefore set forth.

LYMAN DERBY.

In presence of—

HORATIO DORR,
EDWARD HINLAND.
